UNITED STATES PATENT OFFICE.

MAURICE LACHMAN, OF NEW YORK, N. Y., ASSIGNOR TO UNIVERSAL ELECTRIC WELDING COMPANY, OF NEW YORK, N. Y., A CORPORATION OF NEW YORK.

SHEET-METAL PANEL-WORK.

1,154,254.

Specification of Letters Patent. Patented Sept. 21, 1915.

Application filed November 5, 1909. Serial No. 526,347.

To all whom it may concern:

Be it known that I, MAURICE LACHMAN, a citizen of the United States, and a resident of New York, in the county of New York and State of New York, have invented certain new and useful Improvements in Sheet-Metal Panel-Work, of which the following is a specification.

My present invention relates to sheet metal work and more particularly to the forming of panels in sheet metal for doors, wainscoting or other uses.

The main object of my invention is to simplify and cheapen the cost of manufacturing metal panel work by forming the panel or panels from a single sheet of metal thereby avoiding the necessity of soldering or otherwise securing the panels to the frame.

A further object is to secure more artistic and sharply defined paneling than has heretofore been attained from a single sheet of metal.

My invention contemplates the use of a folding operation in contradistinction to a pressed metal operation, the latter being open to the objections that sharp edges cannot be attained and separate and specially formed dies are necessary to make the different size and style panels which are never clearly or sharply defined.

To these ends my invention consists in the method of forming the panels herein-after more particularly described and then set out in the claims.

In practising the invention and in making up the product, a preferably square opening is formed in a blank of sheet metal at a place therein where it is desired to have a corner of the panel. This step differs from anything previously done in that the opening is surrounded on all sides by the metal of the sheet and which metal is continuous, that is, it is not cut or severed. The metal is then folded along lines continuous with the sides of the openings by means of suitable dies until the openings entirely close. According to the way the metal is folded, different arrangements of the panels may be attained, that is, the number of different planes in which the panels are located can be varied.

In the accompanying drawings, Figure 1 is a plan view of a blank prepared in accordance with my invention and indicating by

dotted lines the lines on which the blank is folded to obtain the panels. Fig. 2 is a perspective view showing the blank when folded along the lines in one direction. Fig. 3 is a perspective view of the sheet after the blank has been folded transversely to the foldings shown in Fig. 2 and shows the finished panels. Fig. 4 is a perspective view of another way the same blank may be folded to form panels differently disposed. Fig. 5 is a section taken on the line X-X 65 Fig. 3. Fig. 6 is a section taken on the line Y-Y Fig. 4.

1 indicates a piece of sheet metal which might be of any desired size and proportion according to the disposition desired of the finished panels.

2 indicates openings stamped or otherwise suitably formed in the sheet 1, each opening being disposed or formed at a point where it is desired to have a corner of the panel. 75 The said openings 2 are formed as a square, the length of the sides of which is determined by the height or depth it is desired to have the panel, the length of a side being the height or depth to which the finished 80 panel will rise or be depressed. The sides of one opening are arranged parallel with the side of the other openings, the position of the openings being varied to obtain different size or shape panels. After the openings are formed in their proper locations, the sheet is then folded along the dotted lines 3 by means of suitable dies into a number of parallel rises 4 and depressions 5 as shown in Fig. 2. The sheet is then folded 90 transversely to the rises 4 and depressions 5 and along the dotted lines 6 until the openings 2 are entirely closed. By varying the style of dies used either the form of finished panel work shown in Fig. 3 or that 95 shown in Fig. 4 will then be obtained, the different forms of dies to be used being self-evident and well-known to those skilled in the art and therefore not herein shown.

In Fig. 3 the panels are disposed in three different parallel planes, the uppermost raised panel 7 which is the most predominant, having the intermediate panels 8 emanating from each side of it in a lower plane and connecting it to the base or lowermost panels 9. In Fig. 4 the panels are located in but two planes, being alternately raised and depressed. It will be noted that

the only place the metal is severed or cut is at the corner edges of the panels, the entire other surrounding metal being continuous and uncut.

What I claim as my invention is:

- 5 1. The method of forming a raised panel in sheet metal, consisting in providing closed openings within the body of the metal and disposed at each corner of the desired panel, 10 folding the metal in parallel lines along two sides of the openings and then folding the metal in parallel lines along the other sides of the openings until the openings close.
- 15 2. The method of forming a multiplicity of panels within a body of sheet metal, consisting in providing a blank of sheet metal with a multiplicity of square openings within the body and one at each corner of each desired panel, folding the metal in parallel 20 lines along two sides of all the openings and then folding the metal transverse to said first folds along the other sides of the openings, whereby a plurality of rows of indi-

vidual panels lying in three different parallel planes.

- 25 3. The method of forming a raised panel within a body of sheet metal, consisting in providing a blank of sheet metal with a multiplicity of square openings one at each corner of the proposed panels, the sides of 30 said openings being equal to the desired depth or height of the panel, folding the metal along the sides of the openings in parallel lines at two of the corners and then folding the metal transversely thereto along the sides of the openings in the other corners whereby a plurality of duplicate, square panels are formed within the body of the blank.

Signed at New York in the county of New 40 York and State of New York this 3d day of November A. D. 1909.

MAURICE LACHMAN.
